UNITED STATES PATENT OFFICE.

CHARLES MARK JACOBS AND ROBERT JAMES INSELL, OF READING,
ENGLAND.

SIGNALING ON RAILWAYS.

No. 835,951.

Specification of Letters Patent.

Patented Nov. 13, 1906.

Application filed July 2, 1906. Serial No. 324,452.

To all whom it may concern.

Be it known that we, CHARLES MARK JACOBS, residing at St. Cuthberts, Alexandra Road, Reading, and ROBERT JAMES INSELL, 5 residing at 17 Russell street, Reading, in the county of Berks, England, subjects of the King of Great Britain, have invented certain new and useful Improvements Relating to Signaling on Railways, of which the following 10 is a specification.

In United States patent application filed on October 30, 1905, Serial No. 285,163, by Jacobs, Insell, Newton, and Bowden is described a signaling device for use on railways. 15 wherein a lever carried by the train is operated by a ramp on the line at each signaling position for the purpose of opening an electric circuit on the train to give a danger-signal. When the line is clear, the signalman 20 connects a conductor on the ramp with the battery in his cabin. As the train passes over the ramp the said conductor becomes, through the lever carried by the train, a part of a second circuit carried by the train, 25 which is thus closed. The current in this circuit restrains the danger-signal, which otherwise would have been given and at the same time operates an all-right signal. When this signaling device is to be adopted on a 30 single line of railway, it is desirable that trains going in one direction should receive no signal at all at certain ramps, these ramps being supplied merely for signaling trains going in the other direction. For this purpose, ac- 35 cording to the present invention the conductor on the ramp applying to a train which is to receive no signal is connected by the signalman with his battery in such a manner that the current flows through the second cir- 40 cuit on the train in such a direction that it fails to operate a polarized relay which is substituted on the train for the all-right signal of the former arrangement. When the ramp is to apply to a train which is to receive a 45 signal, the connection of the conductor with the battery is such that the current flowing through the second circuit on the train operates the polarized relay to close a third circuit carried completely on the train, which controls the all-right signal. Whether or not the current that flows through the second circuit on the train operates the relay, it is nevertheless able to restrain the danger-signal by energizing an electromagnet in that

circuit, which operates to restrain the danger- 55 signal notwithstanding that the ramp has lifted the lever and opened the circuit first above mentioned.

In the accompanying drawings, Figure 1 is a side elevation of a part of a locomotive 60 provided with signaling devices such as are described in specification to United States patent application above referred to modified according to the present invention for use when the locomotive is running on a single line. Fig. 2 is a diagram illustrating the combination of the invention with an ordinary electric staff apparatus with which single lines of rail are generally worked. 65

In the circuit of the battery *a*, carried by 70 the locomotive, is an electromagnet *b* and a switch *c*. The armature *b'* of the electromagnet is carried by a lever (not here shown) that controls the valve of the locomotive-whistle, and when the magnet *b* is energized, 75 as is normally the case, it retains the armature to keep the said valve closed. The arm *c'* of the switch *c* is operated by a lever *d* in whose path as the train travels is a ramp *e*. When the lever rides up the ramp, it is lifted 80 sufficiently to move the arm *c'* off the contacts of the switch *c*, whereby the circuit of battery *a* is broken, the magnet *b* is deenergized, and the lever carrying the armature *b'* falls to open the valve of the whistle. 85

The details of the construction so far as described do not differ from those of the corresponding construction shown in the aforesaid specification.

The lever *d* is insulated from the mass of 90 the locomotive, as described and shown in the said specification, and the ramp *e* carries along its whole length an electric conductor *e'*, which can be connected by the signalman either with the positive pole of a battery *e²* or 95 the negative pole of a battery *e³*. The circuit is in either case completed through the lever *d*, an electromagnet *f*, the frame of the locomotive, and earth. The armature *f'* of the magnet *f* is also carried by the lever 100 *d*, which controls the valve of the whistle. It will be obvious, therefore, that whenever the conductor *e'* is connected with either of the batteries *e²* *e³* the magnet *f* is energized and the armature *f'* is retained, so that the whistle does not sound, even though the circuit of battery *a* be broken at switch *c*. 105

The circuit that includes electromagnet *f*

is branched at f^2 , and in the branch is inserted a polarized relay g , whose tongue g' can complete at contact g^2 the circuit of a battery h , carried by the locomotive, which circuit includes an electric bell i . When the signalman connects the positive pole of battery e^2 with the conductor e' , the direction of the current through the polarized relay g is such that the tongue g' turns away from the contact g^2 , and the bell, which is the all-right signal, is not sounded. On the other hand, when the signalman connects the negative pole of battery e^2 with the conductor e' the tongue g' touches the contact g^2 , and the bell is sounded. The signalman has it in his power, therefore, first, to give the danger-signal by not connecting either battery with conductor e' ; second, to restrain the danger-signal without giving the all-right signal by connecting battery e^2 with the conductor e' ; third, to restrain the danger-signal and give the all-right signal by connecting battery e^2 with conductor e' .

Fig. 2 is a diagram showing how this invention is applied to a single line of rail worked by a staff system.

A and B are two signaling-stations which control, respectively, the signaling positions C and D on the section of single line between A and B. At each station there are two levers operating switches k and l , respectively. The contact-fingers of switch k are connected by means of the various leads, as follows: k^1 and k^2 , respectively, with terminals m^1 and m^2 of the electrically-controlled staff instrument, which may be of any known construction, but is here represented as constructed on the principles set forth in the specification to British Patent No. 1,263 of 1889; k^3 , with one pole of battery n , of which the other pole is connected with terminal m^5 of the staff instrument; k^4 , with terminal m^6 ; k^5 , with the conductor e' on the ramp e at C or D, as the case may be, and k^6 with the positive pole of battery o . Of the remaining terminals of the staff instrument, m^3 is connected by the line-wire t with terminal m^3 of the staff instrument at the other station, m^4 with earth, and m^7 with one terminal of polarized relay p , the other terminal of which is connected with terminal m^5 . At each station there is a local circuit including battery q , an electromagnetic lock r , which locks the switch k in each of two positions, and the tongue p' of the relay p . Of the contact-fingers of switch l , l^1 is connected with the negative pole of battery s , and l^2 with the conductor e' .

The details of the staff instrument need not be described here. Suffice it to say that the principle on which it acts is that a staff cannot be removed from or placed in the rack where it remains when not in use without turning a disk. The revolution of the disk for replacing the staff is not locked; but

the reverse revolution for withdrawing the staff is locked electromagnetically, so that the staff cannot be removed until an electric current is sent from the other end of the section of the railway-line. The staff instruments are complicated by various devices for preventing errors; but their essential function requires four switches (marked 1, 2, 3, and 4 in the diagram, Fig. 2.) Of these, switches 1 and 2 are directly operated by the attendant, while 3 and 4 are commutating switches moved automatically by the revolution of the disk when a staff is withdrawn or replaced.

Assuming a train to be ready to start at B to run to A and all the staffs to be in their instruments, the operation is as follows: A turns his switch 2 into the position shown in dotted lines. Thereupon current flows from + pole of his line-battery n to finger k^3 , finger k^4 , terminal m^6 , switch 2, indicator m , switch 4, and terminal m^3 to line t . It will be seen that according to this invention this flow of current can only occur when switch k is in the position shown—namely, that in which contacts k^3 and k^4 are bridged. At B the current thus sent by A enters the staff instrument at terminal m^3 and flows through switch 4, indicator m , switch 2, switch 1, terminal m^7 , polarized relay p , terminal m^5 , switch 3, and terminal m^4 to earth. The circuit is completed through A's staff instrument—namely, through terminal m^4 , switch 3, and terminal m^5 to — pole of battery n . If the current sent by A is in the right direction, the polarized relay p at B is operated to close the circuit of battery q . In the known apparatus this current would have directly unlocked the aforesaid disk to allow B to withdraw a staff as soon as B had moved his switch 1 into the dotted-line position. According to the present invention, however, the current energizes the polarized relay, and so closes the local circuit to unlock the switch k . This enables B to turn the lever of this switch into the position shown in dotted lines, thus bridging the contacts k^1 k^2 , which is essential in order that current may be able to flow through the unlocking-magnet u . Having moved his switch k , B now turns his switch 1 into the position shown in dotted lines. Thereupon current flows from line t , through terminal m^3 , switch 4, indicator m , switch 2, switch 1, terminal m^2 , finger k^2 , finger k' , terminal m' , magnet u , terminal m^6 , switch 3, and terminal m^4 to earth, the circuit being completed through A's staff instrument, as before. B now removes a staff, by which action he turns both switches 3 and 4 into the position shown in dotted lines. Switch 1 having been automatically returned to the position shown in full lines, either by a spring or by the disk turned when the staff is removed, current from line t now flows from terminal

m^3 through switch 4, terminal m^6 , relay p , terminal m^7 , switch 1, switch 2, indicator m , switch 3, and terminal m^4 to earth. Thus the current through relay p is reversed, de-energizing magnet r and again locking switch k in its new position. By moving switch k , B has also bridged contacts k^5 k^6 , thus connecting the positive pole of battery s with conductor e' at D and has insulated contact k^3 from contact k^4 , preventing himself from transmitting current to A's staff instrument. The train now proceeds and in passing D takes up current from conductor e' , so that no danger-signal is given. On the other hand, the relay g , Fig. 1, on the train only closes the local circuit on the train when traversed by negative currents, so that no all-right signal is given. If A wishes to give a danger-signal as the train passes C, he leaves both his switches as they are, whereupon the train receives no current from conductor e' at C and the danger-signal is given. If A wishes to give an all-right signal, he moves the lever of switch 1 into the position shown in dotted lines, thus connecting the negative pole of his battery s with the conductor e' at C. When the train has arrived at A and the staff has been put into A's staff instrument, thus altering the commutator of A's instrument in known manner, A is enabled to send a current of proper direction to B, unlocking the latter's switch K , which must be returned to its original position before B can send current to A. The levers of switches k and l are interlocked, so that the lever of l cannot be moved to connect the negative pole of battery s to conductor e' unless the lever of k is in its normal position. When the train is to run from A to B, the reverse series of operations occur.

Having thus described the nature of this invention and the best means we know of carrying the same into practical effect, we claim—

1. A signaling device for railways, comprising means constituting a normally closed circuit, means constituting a normally open circuit, a separate electrical device contained in each circuit, a danger-signal controlled by each electrical device, a second normally open circuit, means contained in the first normally open circuit adapted to close the second normally open circuit when a current flows in one direction through the first normally open circuit, mechanical means for opening the said normally closed circuit to give the danger-signal when a train passes a signaling-point, means for closing the said first normally open circuit to restrain the danger-signal, and means for determining the direction in which the current shall flow through the said first normally open circuit when it is closed.

2. A signaling device for railways, comprising means constituting a normally closed

circuit, means constituting a normally open circuit, a separate electrical device contained in each circuit, a danger-signal controlled by each electrical device, a second normally open circuit, means contained in the first normally open circuit adapted to close the second normally open circuit when a current flows in one direction through the first normally open circuit, mechanical means for opening the said normally closed circuit to give the danger-signal when the train passes a signaling-point, means for closing the said first normally open circuit to restrain the danger-signal, means for determining the direction in which the current shall flow through the said first normally open circuit when it is closed, and a staff instrument controlling the last-named means.

3. A device for signaling from fixed points on a line of railway to a train passing along the line, comprising a fixed ramp at each signaling-point on the line, a lever carried by the train and adapted to engage with the said ramp, a switch on the train adapted to be opened every time the said lever engages a ramp, an electric circuit carried completely on the train and controlled by the said switch, a danger-signal on the train, an electromagnet in the said circuit adapted when energized to prevent the said danger-signal from operating, an electrical conductor on the said ramp, a second circuit carried on the said train including the said lever and adapted to be closed when the latter engages the said conductor on the ramp, an electromagnet in the said second electric circuit and adapted when energized to prevent the said danger-signal from operating, a polarized relay in the said second circuit, a third circuit carried completely on the train and adapted to be closed by the said polarized relay, and a safety-signal adapted to be operated when the said third circuit is closed.

4. A device for signaling from fixed points on a line of railway to a train passing along the line, comprising a fixed ramp at each signaling-point on the line, a lever carried by the train and adapted to engage with the said ramp, a switch on the train adapted to be opened every time the said lever engages a ramp, an electric circuit carried completely on the train and controlled by the said switch, a danger-signal on the train, an electromagnet in the said circuit adapted when energized to prevent the said danger-signal from operating, an electrical conductor on the said ramp, a second circuit carried on the said train including the said lever and adapted to be closed when the latter engages the said conductor on the ramp, an electromagnet in the said second electric circuit and adapted when energized to prevent the said danger-signal from operating, a polarized relay in the said second circuit, a third circuit carried completely on the train and adapted to be closed by the said polarized relay, and a safety-signal adapted to be operated when the said third circuit is closed.

4
closed by the said polarized relay, a safety-signal adapted to be operated when the said third circuit is closed, a source of electric current beside the line, a switch adapted to connect one pole of the said source with the said conductor on the ramp, and a switch adapted to connect the other pole of the said source with the said conductor on the ramp.

5. On a section of a single line of railway, a ramp adapted for signaling to trains going in one direction, a ramp adapted for signaling trains going in the other direction, an electric conductor on each ramp, a source of electric current beside the line at each ramp, a switch adapted to connect one pole of the source of current with the conductor on the corresponding ramp, a switch adapted to connect the other pole of the source of current with

the conductor on the corresponding ramp, an electrically-controlled staff instrument at each end of the section of line, and means whereby the switch adapted to connect one pole of the source of current with the conductor on the corresponding ramp cannot be operated unless all the staffs are in place in the staff instrument and an electric current has been transmitted from the staff instrument at the other end of the line.

In witness whereof we have signed our names to this specification in the presence of two subscribing witnesses.
